UNITED STATES PATENT OFFICE.

TOM J. SALES, OF SAN FRANCISCO, CALIFORNIA.

RETURN-ENVELOP.

No. 918,919.

Specification of Letters Patent.

Patented March 2, 1909.

Application filed April 1, 1908. Serial No. 424,522.

To all whom it may concern:

Be it known that I, TOM J. SALES, a citizen of the United States, residing at San Francisco, in the county of San Francisco and State 5 of California, have invented a new and useful Return-Envelop, of which the following is a specification in such full and clear terms as will enable those skilled in the art to construct and use the same.

10 This invention relates to a return envelop which is used for the purpose of sending to the place from which the envelop has been sent in the first place matter that is sent out and which must at once be filled up and re- 15 turned to the home office; as is the case with railway reports, express reports, and other mail matter of large companies where one office must report to another on the receipt of a letter from the first office.

20 An object of the invention is to make the envelop as cheap and simple as possible, since for such an envelop as this to meet the competition of the single envelop it must render twice the service with much less than 25 twice the expense.

Another object of the envelop is to provide it with the address of the home office, but in such a place as to be entirely out of the way and out of the sight of the mail clerks, since 30 if they see the name of a large firm on an envelop they do not stop to look at the town, but simply throw it in the pouch for that firm, in at least three times out of five.

Another object of the invention is to place 35 the return address on a sheet that can be easily taken out for the return trip, a pencil being used to force the slip out of the envelop.

Another object of the invention is to provide 40 the sealing flap with a notch which will enable it to be easily torn from the envelop.

In the drawing Figure 1 is a perspective view of the envelop blank, Fig. 2 is a view of the back of the envelop, Fig. 3 is a sectional view of the envelop, and Fig. 4 is a sectional view of one end of the envelop to show the means for securing the sides of the envelop together.

The envelop consists of the body portion 1 50 which has the flaps 2 and 3 on its sides and the narrow flaps 4 and 5 at the ends, the narrow flaps also being formed on the ends of the flap 2. The outer edge of the flap 2 is also provided with the gummed flap 8 which is punched along the line 10 to make it easily 55

separable from the main part of the envelop. The body portion 1 of the blank is provided with a hole 7 of such size as to allow the insertion of a lead pencil and the flap 3 is provided with a hole 6 of such size as to allow the point only of the pencil to pass through. Now it will be noted that when the envelop is ready for its first trip that the flap 3 is placed inside, the hole 6 in register with the larger hole 7. The return address is also 60 placed on this flap. The letter is placed in the envelop, the same being sealed with the flap 8, said flap having a notch 9 cut at one corner to allow the insertion of a knife or pencil to tear the envelop open along the 65 line 10 without injury to the envelop. The gummed flaps 4 and 5 are secured together to produce the envelop. When the first trip has been made the person receiving the envelop takes a pencil and tears the envelop 70 open along the line 10, as above described and then pushes the pencil up through the hole 7 catching the point of the pencil in the small hole 6, and continues to push the pencil up till the flap 3 can be readily pulled out 75 of the envelop with the fingers, when it is ready to be sealed for the return trip.

Having thus described my invention what I claim as new and desire to secure by Letters Patent of the United States is as follows: 80

1. In a return envelop, a blank having a front and a back portion with a hole in it and secured together at their ends, a narrow strip secured to one side of one of said portions, and a second flap secured to the opposite side of the other portion and having a hole that will register with the hole in the 85 back portion of the blank.

2. In a return envelop, a blank having a front and a back portion secured together at 90 their ends the back portion having a hole in it, a narrow strip secured to the front portion, and a wider strip secured to the back portion and on the opposite edge thereof and having a hole smaller than the hole in the 95 front portion and in register therewith when the envelop is to be sealed.

In testimony whereof I have set my hand this 24th day of March, A. D. 1908, in the presence of the two subscribed witnesses. 100

TOM J. SALES.
